UNITED STATES PATENT OFFICE.

MARIE CATHERINE STEICHEN, OF NEW YORK, N. Y.

HAIR WAVER.

Application filed March 3, 1927. Serial No. 172,265.

The objects of this invention are to provide practical, efficient means for producing true Marcel wave effects, which will be of simple, inexpensive construction, easy to use, 5 relatively light in weight and which will hold the hair under sufficient tension to impart the desired wave thereto.

The foregoing and other desirable objects are attained by novel forms of construction, 10 combinations and relations of parts as will be clear from the following specification.

The drawings accompanying and forming part of this specification illustrate a number of practical embodiments of the invention. 15

Figure 1 is a front view, and

Figures 2 and 3 are end views illustrating a pivotally connected form of expanding waver.

20 Figures 4 and 5 are front and end views respectively of a spring wire form of the device.

Figure 6 is a perspective view of a spring waver made out of flat stock.

25 Figures 7 and 8 are cross sectional views as on line 14—15 of Figure 6.

Figure 9 is a plan view of this form of the device.

In Figures 1 to 3 the device is shown constructed in two longitudinally separable parts 1, 2 each having curved prongs or hooks 3 generally similar to the structure in Patent 1,480,638 of January 15th, 1924.

The two parts of the stem are pivoted together at the opposite ends by pivot studs 19 in lugs 20 projecting angularly from the inner sides of the two parts. A spring 21 connected between the studs or end extensions 22 of the two members serves, in conjunction with the angular pivot lugs as a spring toggle to snap the members from the closed position indicated in Figure 2 into the open or expanded condition shown in Figure 3. Angularly projecting handles 23 are shown provided on the ends of the members to aid in thus snapping the device from one position into the other.

The device may be made in a single piece of spring material, as indicated in Figures 4 and 5, where the stem is indicated at 24 having the hooks or prongs 25 of elastic or springy material projecting from opposite sides of the same. This device may be made of spring wire or other suitable resilient material and it is shown as having integral hooks 26 at the opposite ends of the

same for holding the opposite ends of the lock of hair.

In Figures 6 to 9 the device is made of a single piece of light thin sheet metal shown 60 as springy aluminum having the form of a narrow back 27 and ribs or prongs 28 extending in staggered relation from opposite sides of the same, said ribs merging into the back on curved lines at 29 to prevent 65 cutting or tearing the hair.

The number and spacing of these prongs, as in the other instances given, may vary. In Figure 9 the ribs on opposite sides are shown as offset longitudinally a distance 70 substantially equal to the cross section of a normal or average lock of hair as represented by the lines 30 so that the hair will extend substantially transversely across the back when interlaced beneath the prongs. 75

The ribs may be curved or bent down at any desired angle, for instance, substantially at right angles as shown in Figure 7 so that they will be spread somewhat as shown in Figure 8 by the tensioning of the hair there-over. If the tension is not sufficient after the hair is wound on the form, the prongs may be pinched together.

The ends of the back are shown as having 85 tapered extensions 31, 32, turned back over the top of the same and forming clips for securing the ends of the lock. The upper clip is shown as extending down substantially as far as the second prong so that a lock of hair which has first been passed beneath the clip and then carried under the first prong will, in passing across the back to the second prong, overlie the end of the clip and so bind it in gripping engagement 90 on the lock. The lower clip is shown as 95 shorter and as not extending quite all the way back to the last prong so that the end of the lock may be readily passed beneath the same when making it fast. Usually, a few turns of the coil beneath this clip will 100 be sufficient to hold the hair tensioned on the form.

In this last form of the invention, the device may be shipped flat and then bent to shape when it is to be used. The device may be made of any material possessing the desired resiliency and the prongs may be shaped round instead of flat. Preferably when made flat, the ends are rounded off as indicated so as to present no sharp corners. 110

In all forms of the invention the prongs can be pinched together so as to tighten or

tension the lock of hair across the back. This is an important advantage because it is this tension which gives the desired wave and makes it last. This also is an advantage in actual use because the hair can be quickly wound over the form without special regard as to tension and then the required tension be applied afterward by simply pinching the prongs together, the latter being made possible because of the springy or pliable character of the structure.

What is claimed is:

1. A hair waver comprising a normally straight but bendable flexible back and integrally connected flexible prongs branched from the opposite sides of said back and bent from such opposite sides toward each other and toward a generally parallel relation, forming yieldable down turned hooks beneath which a strand of hair laced across the back may be caught, said hooks being yieldable to the strand and capable of being pinched together to tension the strand and bendable extensions at the ends of the back and adapted to be folded down over the back to form hooks for securing opposite ends of the strand of hair, all whereby the strand may be secured and properly tensioned by bending the waver accordingly and whereby because of its pliability the waver will meet the comfort of the wearer.

2. A hair waver comprising a substantially straight back having prongs branched from opposite sides of the same and extending from such opposite sides toward each other and toward a generally parallel relation to thereby provide down turned hooks beneath which a strand of hair laced across the back may be caught, said back and prongs including resilient springy structural means enabling the prongs to be pinched together after the strand is interlaced therewith for the purpose of tensioning the strand over the waver.

3. A hair waver comprising an elongated back of inherently resilient springy flat sheet material having integral prongs projecting from the opposite edges of the same and bent from the generally flat plane of the back substantially at right angles to said plane to thereby provide down turned hooks beneath which a strand of hair laced across the back may be caught and an integral elongated extension at one end of the back bent in reversed relation over the top of the back and of sufficient length to overlie a plurality of the turns of hair laced across the back.

In witness whereof, I have hereunto set my hand this 2nd day of December, 1924.

MARIE CATHERINE STEICHEN.
